UNITED STATES PATENT OFFICE.

CHAUNCEY C. CHAMBERLAIN, OF IONIA, MICHIGAN.

SPARKING IGNITER FOR EXPLOSIVE-ENGINES.

SPECIFICATION forming part of Letters Patent No. 715,196, dated December 2, 1902.

Application filed December 12, 1901. Serial No. 85,661. (Model.)

To all whom it may concern:

Be it known that I, CHAUNCEY C. CHAMBERLAIN, a citizen of the United States, residing at Ionia, in the county of Ionia and State of Michigan, have invented certain new and useful Improvements in Sparking Igniters for Explosive-Engines; and I do hereby declare the following to be a full, clear, and exact description of the invention, such as will enable others skilled in the art to which it appertains to make and use the same.

My invention relates to improvements in igniters for gas or hydrocarbon engines; and it consists in the construction and arrangement of its parts, which will be more fully hereinafter described and definitely pointed out in the claims.

The objects of my invention are to devise a device which will produce sparks intermittently and regularly within the explosive-chamber, so that the explosions will take place in regular succession, as required by the speed of the engine, to produce one which is simple in its construction, quick and positive in its action, easily and cheaply manufactured, consisting of but few parts which are not liable to get out of order, being so formed and assembled as to admit of but very little friction while in operation. I accomplish these objects by means of the device herein described, and illustrated by the accompanying drawings, in which—

Figure 1 is a plan view, in part, of a cylinder-bed and combustion-chamber of an ordinary gasoline-engine with my improved device attached thereto. Fig. 2 is an end view of the same with a portion of the combustion-chamber broken away to show the igniting portion of the device within the same. Fig. 3 is an enlarged detail plan view of supporting-plate and fixed and movable electrodes with their attachments detached from the igniter-chamber, also shows the means for operating said movable electrode. Fig. 3^A is a side view of same, the means for operating having been removed therefrom. Fig. 4 is an enlarged detail end view of the supporting-plate and movable electrode with its attachments detached from the igniter-chamber, the means for operating said movable electrode shown in Figs. 1 and 2 having been removed therefrom. Fig. 5 is an under side

view of the same. Fig. 6 is a plan view of my improved actuating-bar with its actuating hook and spring attachment. Fig. 7 is a side view of same. Fig. 8 is a detached end view of the actuating-hook. Fig. 9 is a plan view of my improved electrode-controlling collar. Fig. 10 is an end elevation of the same, and Fig. 11 is a part elevation and sectional view of my improved rock-arm and cap with spring attachment. Fig. 12 is a part plan and sectional view of my device with the cap portion J removed to show the arrangement of the electrode-controlling collar M on the shaft b².

Referring to Fig. 1, A indicates a cylinder of an ordinary gasoline-engine, B a base for its support, and C the igniting-chamber. D is a supporting-plate having a diagonally-extended arm E formed therewith. Said arm E gradually tapers to its outer end, where upwardly and downwardly projecting bosses a and a' are formed. I is a cylindrical boss formed on the under side of the supporting-plate D, Figs. 4 and 5, and its purpose is to provide rigid bearings for the fixed electrode-shaft b¹ and movable electrode-shaft b². The supporting-plate D is removably secured to the igniting-chamber C by means of cap-screws c', as shown in Figs. 1 and 2. The inner or lower end of the fixed electrode-shaft b¹ has a sparking-point d extending outward at a right angle thereto. Said electrode-shaft a' is threaded at its outer upper end portion and is secured within the supporting-plate D and cylindrical boss I by means of lock-nuts b³ and a suitably-insulated washer b⁴ extending into a hole made part way into the upper portion of said supporting-plate D. Its shaft a' is also provided with suitable insulating material. Electric connection is made to the interior of the igniting-chamber C by means of a wire e, battery F, wire e', and pole e², as shown in Figs. 1 and 2. G is a movable electrode having attached to its lower or inner shaft end b² a contacting arm c², at which outer free end is a sparking-point d', its purpose serving to make and break the circuit to cause the gases contained within the igniting-chamber c to explode, which explosion occurs at regular intervals while the engine is in motion. The opposite extreme upper end of the movable

electrode G has on its shaft b^2 a cap J, which is secured by means of a pin f, as shown in Fig. 4. Said cap J has a series of holes f' extending around and through it, near its outer circumferential surface.

Referring to Figs. 1, 2, 3, 3^A, and 4, K indicates a rock-arm which has an upward-extended sleeve L, Fig. 11, at one end of the same and has a hole m extending through it. It is loosely mounted on the shaft b^2 of the movable electrode G. N is an adjustable coil-spring mounted on the sleeve L of the rock-arm K, one end of which is bent up and removably secured to the cap J on the end of the shaft b^2 of the movable electrode G by means of hole f², in which it is inserted. The opposite or lower end of said coil-spring N rests on the shouldered portion l² thereof and is bent to conform to the contour of rock-arm K at its thickest part near the sleeve L and is secured thereto. The purpose of the holes f' in cap J is for adjustment in order to give a greater or less tension to the coil-spring N should it at any time be desired to produce a quicker or slower action of the rock-arm K. The outer or free end of rock-arm K is narrower, thicker, and heavier than at the part where its sleeve L extends, from which point it tapers to a rounded point n. The contact-surface o of said rock-arm K is on the same perpendicular plane as the center of the shaft b^2 of the movable electrode G, on which it is loosely mounted. The purpose of the sleeve L on the rock-arm K, as hereinbefore described, is to reduce friction between the coil-spring N and movable electrode-shaft b^2 , and this is accomplished by reason of the rock-arm K moving in the same direction with the coil-spring N while in action. A further purpose of sleeve L is to provide for a longer bearing for rock-arm K, so that it will not drop down at end. M is an electrode-controlling collar having a downward-projecting sleeve m' formed thereon, with a hole m² extending therethrough, Figs. 9, 10, and 11. One end of said electrode-controlling collar M is semi-elliptical in form, (immediately above its sleeve m'), and it gradually tapers to a rounded point p at its opposite end, at which end a pin p' extends upward and bears against the perpendicular surface of rock-arm K. Said electrode-controlling collar M is arranged on the shaft b^2 of the movable electrode G immediately below the rock-arm K on a horizontal plane to it, its longest diameter being diagonal to and at a right angle to the perpendicular surface o of said rock-arm K. It is rigidly secured to the shaft b^2 of the movable electrode G at an angle of about thirty degrees by means of a pin p², (shown in Fig. 4,) its lower surface being adjacent to the upper surface of the supporting-plate D. The use and purpose of the semi-elliptical portion j' of the electrode-controlling collar M are to form a lever, against which the spring P presses, thus preventing a rebounding of the sparking-point d'. P is

an angular tension-spring, which is secured to the upper surface of the supporting-plate D by means of a screw g, and it is set at a slight angle to the shorter axis of the elliptical portion j' of the electrode-controlling collar M, its purpose being to prevent the rebounding of the movable electrode G immediately after a spark is produced within the igniting-chamber C. Secured on the supporting-plate D is a stop a, which is flattened on one side to form a flat bearing, against which the free end of the rock-arm K strikes. Its purpose is to limit the backward movement of said rock-arm K after its release from the actuating-hook R. It is flattened to provide against the wear on its surface by reason of the blows received from the rock-arm K and is perpendicular to and on the same plane as the center of the movable shaft b^2 . R is an actuating-hook inserted in an angular-shaped slot S, formed in one end of an actuating-bar T and is held in position by means of a pin t passing through it and the forked portions u² u³ of said actuating-bar T. Its outer free end is angular in form and is concavely beveled, as at v, the perpendicular depth of same being equal to the perpendicular depth of the rock-arm K at its outer free end portion, which it engages. w is a rounded lug formed on the end of the actuating-hook R diagonally to its contact-surface v', and it engages an angular looped spring t', secured to the upper surface of the actuating-bar T at its outer free end by means of a screw u' inserted in it, and its purpose is to return the actuating-hook R to its normal position after it has been released from the rock-arm K upon the forward and backward movement of the actuating-bar T. The actuating-hook R is flattened and elongated at its engaged portion s² and fits within the slotted portion of the actuating-bar T, within which it oscillates by means hereinafter described. The slot S in the actuating-bar T is formed angular at its inner end to provide a bearing y for the outer upper end of actuating-hook R, which bears against it while in its normal position; also, to allow free oscillating movement of said actuating-hook R on the pin t after it has become disengaged with the free end of rock-arm K upon the backward movement of the actuating-bar T. V is a reciprocating lever, one end of which rests upon the upper surface of a boss a, formed on the upper surface of the supporting-plate E. It is loosely secured thereto by means of a pin v² passing through it to the lower surface of the boss a', formed on the under surface thereof. Said reciprocating lever V is bent and also loosely secured at its opposite end to the under side of actuating-bar T by means of a pin t² passing upward through the actuating-bar T. t⁴ is a connecting-rod secured in the end of actuating-bar T opposite to its slotted portion S, its purpose being to convey motion from the engine to actuating-lever R.

The operation of my device is as follows:

Motion having been given to the actuating-bar T, supported on the reciprocating lever V, by means of the engine with its connections, actuating-hook R carries forward with it, as indicated by the arrow, Fig. 3, the rock-arm K to a portion of its stroke, (indicated by the dotted lines,) at which portion the sparking-point d' of the movable electrode G comes in contact with the sparking-point d of the fixed electrode H, which completes the circuit immediately before a spark is produced within the igniting-chamber C, and on a further continuation of the stroke the rock-arm K moves independently on the movable electrode-shaft b², while the said movable electrode-shaft b² and the sparking-point d' remain stationary by reason of the sparking-points having come in contact with each other. The purpose of the angular spring is to prevent the sparking-points d and d' from coming together prematurely, which they otherwise would by reason of the vibratory or jarring movement of the engine should it not be placed on a firm or solid foundation. The rock-arm K being mounted loosely on the electrode-shaft b² and being spring-held against pin p' on electrode-controlling collar M until the sparking-points d and d' come in contact with each other, a further forward movement of the actuating-hook R will cause the rock-arm K and pin p' to separate and remain separated until the actuating-hook R has become released from contact with the rock-arm K, while actuating-bar T is still moving forward. The actuating-hook R being fulcrumed by the pin t below and to the right of its horizontal center, it will be understood that there will be no friction at the points of contact until the contacting point of actuating-hook R has passed the dead-center on the pin t of said actuating-hook R, from whence it will have frictional contact with rock-arm K, but only for an instant, and will become suddenly released (on account of the difference between the leverage of said rock-arm K and actuating-hook R) and rock-arm K will be suddenly and backwardly rotated to its normal position by reason of the resilient action of the coil-spring N. The electrode-controlling collar M being secured diagonally on the movable electrode-shaft b², having its pin portion p' abutting the contact-surface of the rock-arm K at its inner shaft end portion, the rock-arm K will strike the said pin portion p' of the electrode-controlling collar M immediately before it does the stop Q, which will cause the sparking-points d and d' to be instantly separated from each other. Thus a spark will be produced within the igniting-chamber C. Upon a return stroke of the actuating-bar T the concave portion v of the actuating-hook R will strike the rounded portion n of the rock-arm K, and it will have become forced backward by its own movement on the pin t toward the angular portion of the slot S in the actuating-bar T.

By the foregoing description it will be seen

that sparks are produced within the igniting-chamber C only upon the forward movement of the actuating-bar T.

Having thus fully described my invention, what I claim as new, and desire to secure by Letters Patent, is—

1. In a sparking device for explosive-engines, the combination with the boss within the igniting-chamber, of a fixed electrode-shaft extending therethrough and suitably insulated therefrom and provided with a sparking-point, a movable electrode-shaft extending therethrough and provided at the inner end with an arm and a sparking-point, a rock-arm having an extended sleeve portion formed at a right angle thereto and made smaller to form a shoulder therewith, and mounted loosely on the movable electrode-shaft, a coil-spring loosely mounted on the sleeve portion of the rock-arm, one end of which is secured to a cap on the extreme outer end portion of the movable electrode-shaft and the other to the rock-arm at its inner, shaft end portion, an electrode-controlling collar having an elliptical portion mounted on and fixedly secured to the movable electrode-shaft, immediately below, and adjacent to said rock-arm, and having its outer and upper free end portion abutting the same, and an angular tension-spring, the upper perpendicular portion of which bears against the elliptical portion of said electrode-controlling collar, having its lower horizontal portion secured to the supporting-plate which is removably mounted on the igniting-chamber of the engine, a stop secured in the upper portion of said supporting-plate adapted to limit the movements of the rock-arm and electrode-controlling collar in combination with an automatic releasing mechanism consisting of an actuating-bar having an angular-shaped slot formed therein at its outer free end portion, and a bearing formed therewith, an actuating-hook loosely mounted therein having its free outer end portion beveled and concavely formed, a pin extending through it and the forked portions of said actuating-arm, a lug formed thereon at its opposite point of contact, angular looped spring secured to the upper surface of the actuating-bar at its outer free end portion, adapted to engage the lug on the actuating-hook, a reciprocating lever, one end of which is mounted on the outer end of the arm formed with the supporting-plate and the other to the actuating-bar which carries it forward and backward by means substantially as described.

2. In a sparking device for explosive-engines, the combination with the boss I, within the igniting-chamber C, of a fixed electrode-shaft b², extending therethrough, and suitably insulated therefrom and provided with a sparking-point d, a movable electrode-shaft b², extending therethrough, and provided at its inner end with an arm c², and sparking point d', a rock-arm K, having an extended sleeve portion L, at a right angle to its free

end or contact portion o , which contact portion is on the same perpendicular plane as the center of the shaft b^2 , on which it is loosely mounted, a coil-spring N , loosely mounted on 5 the sleeve portion L , of the movable electrode-shaft b^2 , one end of which is secured to a cap J , on its extreme outer end portion and the other to the rock-arm K , at its inner shaft end portion, an electrode-controlling collar M , 10 mounted on and fixedly secured to the movable electrode-shaft b^2 , its longest diameter being diagonal to, and at a right angle to the perpendicular surface o , of said rock-arm K , immediately below and adjacent to said rock-arm K and having its outer and upper free 15 end portion abutting the same, and an angular tension-spring P , having its upper perpendicular portion p^5 , bearing against the elliptical portion j' , of said electrode-controlling collar M , and having its lower horizontal portion q , secured to the supporting-plate D , which is removably mounted upon the igniting-chamber C , of the engine, a stop Q , secured to the upper portion of said supporting-plate D , adapted to limit the movements of rock-arm K , and electrode-controlling collar M , in combination with an automatic releasing mechanism having suitable 25 means for operating it from the engine-shaft, 30 substantially as described.

3. In a sparking device for explosive-engines, the combination with the boss I , and fixed electrode-shaft b' , having a sparking-point d , a movable electrode-shaft b^2 , extending therethrough and provided with an arm c^2 , and sparking-point d' , a rock-arm K , having contact-surfaces o and n , in combination with an extended sleeve portion L , with its shoulder l^2 , loosely mounted on the movable electrode-shaft b^2 , a spring N , loosely mounted 35 on the sleeve portion L , of said movable electrode-shaft b^2 , one end f^3 , of which is removably secured to a cap J , having holes f' , f'' , formed therein and the other to the rock-arm K , at its inner shaft end portion, an electrode-controlling collar M , having upward-extending pin portion p' , elliptical portion j' and sleeve portion m' , near its shaft end portion b^2 , on which it is mounted and fixedly se- 40 45

cured thereto, of an angular tension-spring P , secured to the supporting-plate D , having its upper end portion engaging with the elliptical portion j' , of said electrode-controlling collar M , a stop Q , secured in the upper portion of the supporting-plate D , in combination with an automatic releasing mechanism consisting of an actuating-bar T , having an angular-shaped slot S , and bearing portion y , formed therewith, an actuating-lever R , having the flattened and elongated portion s^2 , concave bevel portion u , and a lug portion w , mounted loosely therein and secured by means of a pin t , passing through it and the forked portions u^2 , and u^3 , a spring t' , adapted to engage the lug w , of the actuating-lever R , a reciprocating lever V , loosely secured to the arm E , of the supporting-plate D , and actuating-lever T , which carries it substantially as described. 50 55 60 65 70

4. In a sparking device for explosive-engines, the combination with the igniting-chamber C , and boss I , of a fixed and movable electrode mounted therein, a movable electrode G , consisting of a shaft b^2 , having a suitable sparking-point at its inner end, 75 and cap J at its outer end, a rock-arm K , mounted loosely thereon, having contact-surfaces o and n , at its free end and an upward-extending sleeve L , with a shoulder l^2 , formed therewith at its opposite shaft end, a spring N , mounted loosely on the sleeve portion of rock-arm K , having its upper end secured in cap J , and its lower end to the inner shaft portion of said rock-arm K , in combination with an electrode-controlling collar M , having an upward-extending pin p' , at one end and sleeve portion m' and an elliptical portion j' , at its opposite or shaft end portion, adapted to bear against the upper end portion of a spring P , and a stop Q , substantially as de- 80 85 90

In testimony whereof I affix my signature in presence of two witnesses.
